THERMO-SENSITIVE PUMP

Edward J. Herbenar, Detroit, Mich., assignor to Thompson Products, Inc., Cleveland, Ohio, a corporation of Ohio

Application April 25, 1955, Serial No. 503,630

10 Claims. (Cl. 103—97)

This invention relates to pumps having pumping rates varying automatically in response to the temperature of fluid being pumped.

Specifically, this invention deals with a pump rotor or impeller with thermosensitive pumping elements which change position in response to temperature changes to increase or decrease the flow rate through the pump.

In its preferred forms the rotor or impeller has a slotted peripheral wall in communication with the inlet and outlet of the pump. Thermo-sensitive bi-metallic pumping vanes control flow through the slots and shift position to vary their fluid displacing capacity. When the bi-metallic members are in an open position they project from the rotor to form pumping vanes. When in a closed position the bi-metallic members hug the impeller wall and close the slots so that rotation of the impeller will not create a propelling of fluid and will block flow between the pump inlet and outlet. Between fully opened and fully closed positions the bi-metallic members may assume intermediate positions to provide intermediate pumping rates for the pump.

While the bi-metallic elements are preferably arranged to increase their pumping rates as they increase in temperature, a reversed arrangement can be provided, if desired, without departing from this invention, whereby the pumping rate will increase upon a decrease in temperature.

Accordingly, a feature of this invention is to provide a thermo-sensitive pump which automatically varies its pumping rate in accordance with the temperature of its pumping elements.

It is also an object of this invention to provide an inexpensive thermo-sensitive pump.

A further object of the invention is the provision of a thermo-sensitive fluid impeller which has a variable pumping rate controlled by its temperature.

A further object is to provide a centrifugal pump with bi-metal vanes which shift in response to temperature changes for varying the pumping rate.

Another object of the invention is to provide a pump impeller with a slotted peripheral wall carrying bi-metal elements to control flow through the slots and to project from the wall to form pumping vanes.

Still another object of this invention is to provide a thermo-sensitive coolant pump for an automobile engine or the like which automatically controls flow of coolant through the engine circulating system in response to coolant temperature, thereby avoiding the necessity for a thermostat valve.

Other and further objects of the invention will be apparent to those skilled in the art from the following detailed description of the annexed sheets of drawings which, by way of examples only, illustrate two embodiments of the invention.

The drawings:

Figure 1 is a fragmentary cross sectional view with parts in elevation of a centrifugal fluid pump embodying features of the present invention;

2

Figure 2 is a cross sectional view taken on the line II—II of Figure 1 further illustrating features of my novel fluid pump construction;

Figure 3 is a fragmentary cross sectional view similar to Figure 1 but showing a modified impeller construction;

Figure 4 is a fragmentary cross sectional view taken on the line IV—IV of Figure 3 further illustrating my novel modified impeller construction; and

Figure 5 is a side elevational view of my modified impeller construction.

As shown on the drawings:

The numeral 10 indicates generally my novel centrifugal fluid pump assembly which may be used with an automobile or the like and when used prevents the circulation of fluid until the fluid reaches a predetermined temperature.

The pump 10 has a casing 11 defining a chamber or housing 12 having a fluid inlet 13 and outlet 14. Extending into the casing 11 is a drive shaft 15 which has a suitable shaft bearing assembly 16 for carrying same. Suitably secured to one end of the drive shaft 15 is a hub 17 which is in turn suitably secured at 18 to a pulley 19. The pulley 19 is suitably adapted to be belt driven by a prime mover (not shown).

Suitably secured to the other end of the drive shaft 15 is a second hub 20 which carries a suitable shaft seal 21 and a second seal 22 bearing upon flange 23 of casing 11.

Suitably carried on the terminal end of drive shaft 15 adjacent hub 20 is a cup-shaped disk or rotatable impeller 24 which is carried within housing 12 of the centrifugal pump 10.

The cup-shaped disk or impeller 24 includes a main generally radially extending annular section 25 with a generally axially extending annular flange 26 on the terminal end of radial section 25. The annular flange 26 has a plurality of circumferentially spaced slots 27 defining connecting channels between the fluid inlet 13 and outlet 14 for receiving therethrough fluid. Suitably secured by a rivet or the like on the inlet or downstream side of the slot 27 and extending over to close same is a laminated heat responsive bi-metallic element 28.

The bi-metallic element 28 may be made of any suitable metals or the like having different coefficients of expansion such as copper and steel with the lamination 28a in closest proximity to the slot 27 suitably of a higher coefficient of expansion than the outer lamination 28b since the desired curling action seen in Figure 2 is in that manner most readily obtainable.

In other words, as the heat of fluid heats the bi-metallic element 28 the lamination 28a having a higher coefficient of expansion expands to a greater extent than the lamination 28b which has a lower coefficient of expansion. It is in this manner that the curling of the element 28 is effected to open the slot 27 thereby permitting fluid to be pumped therethrough. The channels or slots 27 remain closed until the temperature of the fluid to be pumped reaches a predetermined temperature at which time the bi-metallic elements become curled as shown by the dotted lines in Figure 2.

Formed with or mounted on section 25 is an annular shouldered abutment or protuberance 29 defining a stop which is located in a predetermined position relative to the respective slots 27. Upon the curling of the bi-metallic elements 28 the respective ends 30 of the same are biased in abutting relation against the stop 29 (Fig. 1). By providing a stop 29 against which the ends 30 of the elements 28 may be shouldered the deformation of the elements 28 may be controlled. It is in this manner that the elements 28 may also be utilized as vanes for facilitating in the directing of fluid into the respective

channels 27. It has been found that by shouldering the vanes or bi-metallic elements 28 as above described, that the high speed action of the driven cup-shaped disk or impeller 24 against the fluid in the housing reduces any propensities of the fluid to so deform the elements 28 that they may not be used as vanes.

As the engine warms up the fluid in the circulating system will reach a given predetermined temperature at which time the heat responsive bi-metallic elements 28 will expand and curl against the annular shoulder 29 on the rotating impeller 24 and thereafter serve in the capacity of vanes to facilitate directing the centrifugally impelled fluid out through the slots 27 into the pump outlet 28.

Figures 3, 4, and 5 illustrate a modified impeller pump construction indicated generally at 32. It will be appreciated that the pump 32 operates in the same manner as the pump 10 shown in Figures 1 and 2 and that the pump 10 is structurally identical with pump 32 excepting the modified impeller construction which will be hereinafter discussed in detail. Where identical elements have been employed in pump 32 as in pump 10 the same numerals have been used.

The impeller 31 includes a main generally radially extending annular section 33 with a generally axially extending annular flange 34 on the terminal end of radial section 33. The annular flange 34 may be made of a metal which has a relatively low coefficient of expansion.

About the circumference of the generally axially extending flange 34 are a plurality of deformable integral cutouts or strips or tabs 35 which have been punched from the flange 34 and deformed inwardly to form openings or slots 36 which define channels communicating the inlet 13 with the outlet of the pump 32.

After the flange 34 has been punched to form a plurality of tabs 35 a strip of material having a relatively high coefficient of expansion such as copper, corresponding in size to the size of the opening or slot 36 is suitably secured to the inner surface of the tab 35. In other words, the copper strip 37 may be welded to the inner surface of the steel or the like tab 35.

In the operation of the pump the tab functions in the same manner as described in connection with the first form of my invention. The tab responds to changes in the fluid temperature and when sufficiently heated the end 38 of the tab progressively curls and eventually is biased against the inner annular shoulder or stop 39. It is in this manner that the slots 36 defining channels communicating the inlet and outlet are opened and closed. After the tabs 35 have sufficiently deformed to open the slots 36 the tabs then serve as vanes to facilitate in directing the centrifugally moving fluid through the slots or channels 36.

From the above description it will therefore be understood that fluid from the inlets 13 of the pumps of this invention flows through the eyes of the pumps into the pump impellers where it is surrounded by the annular impeller peripheries 25 or 34. When the fluid is at an elevated temperature the bi-metal elements 28 or 35 will be curled inwardly from the impeller peripheries to form centrifugal pumping vanes slicing into the fluid and discharging it through the slots 27 or 36 into the surrounding volutes for discharge through the peripheral outlets 14. When the fluid is at a temperature below that which is sufficient to expand the bimetal elements into their curled vane positions, these elements will close the slots in the rotor peripheries to form shut-off valves separating the inlets and outlets.

When the pumps of this invention are used as coolant pumps for liquid-cooled engines the pump rotor provides its own thermostat valve between the engine and radiator and the heretofore necessary extra valve is eliminated without loss of function.

If desired, the pump rotor can be arranged so that the

bi-metal elements swing out instead of in, or so that the curling occurs only when temperature drops below a predetermined degree. Thus placement of the most expansive metal on the inner wall will cause slot closing movement upon increase in temperature and vane curling movement upon decrease in temperature.

Thus this invention provides a simple, inexpensive, thermo-sensitive centrifugal pump assembly which is efficient in operation and easily assembled.

It will be understood that modifications and variations may be effected without departing from the scope of the novel concepts of the present invention.

I claim as my invention:

1. In a fluid pump including a housing connected to a fluid inlet and outlet, the improvement of an impeller movable within the housing, said impeller having an annular axial portion having circumferentially spaced openings therethrough defining fluid channels in communication with the inlet and the outlet, and bi-metallic elements on said impeller and extending over said channels to define valves for opening and closing the channels in response to variations in fluid temperature, said bi-metallic element being comprised of laminated metal strips with the strip in closest proximity to the channel being of a higher coefficient of thermal expansion than the other strip.

2. In a fluid pump including a housing connected to a fluid inlet and outlet, the improvement of an impeller movable within the housing, said impeller having at least one radially extending fluid channel in communication with the inlet and the outlet, at least one bi-metallic element on said impeller with the element having a radially deflectable free end extending over said radial channel defining a valve for opening and closing the channel in response to variations in fluid temperature, the free end of said bi-metallic element when in an open position being radially spaced from the radial channel and defining a vane to direct fluid into the channel, and stop means on said impeller adjacent the channel for limiting the deformation of the heat responsive element.

3. In a fluid pump including a housing connected to a fluid inlet and outlet, the improvement of an impeller movable within the housing, said impeller having at least one opening therein defining a fluid channel in communication with the inlet and the outlet, and at least one bi-metallic element on said impeller and extending over said channel to define a valve for opening and closing the channel in response to variations in fluid temperature, said bi-metallic element being comprised of strips secured together with the strip in closest proximity to the channel being of a higher coefficient of thermal expansion than the other strip and with the other strip being integral with and cut out from the wall of the impeller.

4. An impeller for use in a centrifugal pump having an inlet and outlet including an annular radially extending member having connected thereto an axially extending member, heat responsive valve means on said axially extending member including a channel through said axial member in communication with the inlet and outlet and a bi-metallic element for opening and closing same in response to predetermined variations in fluid temperature, said bi-metallic element when in an open position serving as a vane for facilitating in the pumping of fluid, and stop means on said radially extending member limiting the deformation of the bi-metallic element when in an open position.

5. A combined pump and thermo-sensitive valve which comprises a casing defining a chamber with a central eye inlet and a peripheral outlet, a rotor in said chamber having a slotted peripheral wall communicating with the inlet on the inside and with the outlet on the outside, and bi-metal elements on said wall closing said slots when below a predetermined temperature to block flow from the inlet to the outlet and curling inwardly when heated to form vanes effective to pump fluid from the

inside of the wall through the slots for discharge through the outlet.

6. In a fluid displacing structure including fluid inlet and outlet openings, a rotatable impeller having a dished area in communication with one of the fluid inlet and outlet openings with said dished area defined at its radially outer side by an outer annular impeller wall which wall has a series of radially outwardly extending passageways which are in communication with the fluid inlet and outlet openings, and heat responsive shut-off valve means for aiding in the control of the fluid flow through the inlet and outlet openings comprising a series of vanes, said vanes being mounted on the impeller and extending into the dished area in proximity to the passageways.

7. In a fluid pump including a housing connected to a fluid inlet and outlet, the improvement of an impeller movable within the housing, said impeller having a series of openings therein defining fluid channels in communication with the inlet and the outlet, and bi-metallic elements on said impeller each extending over one of said channels to define a valve for opening and closing the channel in response to variations in fluid temperature, said bi-metallic element when in an open position being turned to define a vane to direct fluid into the channel.

8. In a fluid pump including a housing connected to a fluid inlet and outlet, the improvement of a rotatable member movable within the housing with the rotatable member having a series of passageways therein defining radial fluid channels in communication with the inlet and the outlet, and circumferentially spaced bi-metallic elements on said rotatable member and extending across said channels to define shut-off thermostatic valves for opening and closing the channels in response to variations in fluid temperature.

9. A dished type impeller for use in a centrifugal pump

having an inlet and outlet including an annular radially extending portion and an axially extending portion connected thereto together defining the dish and with the radially extending portion disposed radially inwardly of the axially extending portion, the axially extending portion having radial channels, and heat responsive valve means comprising laminated bi-metallic vanes on said axially extending portion extending over the radial channels in communication with the inlet and outlet, said heat responsive valve means in an open position being bent and deflected radially away from the radial channels and in a bent position comprising a vane for facilitating in the pumping of fluid.

10. In a centrifugal pump having an inlet and outlet, 15 an impeller including an annular radially extending portion and an axially extending peripheral flange having ports connecting the inlet and outlet, and heat responsive valve means on the radially inner side of said axially extending flange, including bi-metallic elements for opening and closing the ports in response to predetermined variations in fluid temperature, said bi-metallic elements comprised of metal strips of different coefficients of expansion with the radially inner strip having the lower coefficient of expansion thereby permitting the other strip 20 in response to increased fluid temperatures to curl the elements away from the ports to open the ports.
